To all whom it may concern:

Be it known that I, Milton Rosenbloom, a citizen of the United States and a resident of Newark, in the county of Essex and State of New Jersey, have invented a new, original, and ornamental Design for a Child's Snowsuit or Similar Article, of which the following is a specification, reference being had to the accompanying drawing, forming a part thereof, wherein:

Fig. 1 is a front elevational view of a child's snowsuit or similar article, embodying my new design;

Fig. 2 is an enlarged fragmentary view of one of the sleeve ends shown in Fig. 1;

Fig. 3 is a similar view of the sleeve end as it appears in unzipped position with one of the flaps turned up;

Fig. 4 is a side elevational view of the sleeve end shown in Fig. 2; and

Fig. 5 is a similar view thereof as it appears in unzipped position with both flaps turned up.

The back of the snowsuit is conventionally plain. The dominant feature of my design resides in the convertible sleeve end portions shown in solid lines.

I claim.

The ornamental design for a child's snowsuit or similar article, substantially as shown and described.
